United States Patent

Des. 236,372
Patented Aug. 19, 1975

236,372

PORTABLE EARTH BORING MACHINE

Richard P. Dunn, Wichita Falls, Tex., assignor to
International Boring Systems Co., Inc., Wichita Falls,
Tex.

Filed Aug. 7, 1972, Ser. No. 278,349

Term of patent 14 years

Int. Cl. D15—04

U.S. Cl. D54—14 R

FIG. 1

FIG. 4

FIG. 3

FIG. 1 is a right-side perspective view;

FIG. 2 is a left-side perspective view;

FIG. 3 is an end view of the invention seen when viewed from the right-hand side of FIG. 1;

FIG. 4 is an end view of the invention opposite to the view in FIG. 3; and

FIG. 5 is a top plan view.

I claim:

An ornamental design for a portable earth boring machine, as shown.
